UNITED STATES PATENT OFFICE.

ARTHUR W. BOCK, OF ANTIOCH, ILLINOIS.

ASH RECEPTACLE AND SIFTER.

1,321,971.

Specification of Letters Patent.

Patented Nov. 18, 1919.

Application filed February 24, 1919. Serial No. 278,589.

To all whom it may concern:

Be it known that I, ARTHUR W. BOCK, a citizen of the United States, residing at Antioch, in the county of Lake and State of Illinois, have invented certain new and useful Improvements in Ash Receptacles and Sifters, of which the following is a specification.

My invention relates to improvements in 10 ash receptacles and sifters.

One of the objects of my invention is to generally improve devices of this character.

Another object is to provide an ash sifter 15 within a receptacle with the latter connected to a smoke flue so that all of the dust or floating ashes, due to handling of the ashes, is carried up the flue by the natural draft thereof, instead of being permitted to freely float about the room and settle on the 20 contents.

Another object of my invention is to provide an improved means for agitating the riddle, or sifter within the closed receptacle, and means for discharging the coal from the 25 riddle into a container outside of the receptacle.

Other, further and more specific objects of my invention will become readily apparent, to persons skilled in the art, from a 30 consideration of the following description when taken in conjunction with the drawings, wherein:—

Figure 1 is a side elevation of the receptacle showing it connected to the smoke flue 35 of the furnace.

Fig. 2 is an enlarged sectional view showing the riddle and the interior of the enclosing receptacle.

Fig. 3 is a section taken on line 3—3 of 40 Fig. 2.

Fig. 4 is an enlarged elevation of the riddle looking at it from the front.

Fig. 5 is a section taken on line 5—5 of 45 Fig. 3.

In all the views the same reference characters are employed to indicate similar parts.

In the drawings 10 is a receptacle connected, as at 11, to a smoke flue 12, of a furnace 13. A laterally projecting part 14 contains a door 15 and another door 16. The first door, to be opened, as shown in dotted lines in Fig. 2, for the purpose of placing ashes to be sifted upon the riddle 17 and 50 the door-way 16 is used for the purpose of placing the ash receiver 18 inside of the

receptacle and for removing it therefrom. The riddle 17 consists of side walls 19 and 20, tapered toward the front, and having a rear wall 21, having preferably a returned 60 flange or edge 22, to give it strength and to increase its holding capacity. The center portion of the floor 23, of the riddle, is covered with a foraminous wire fabric 24, of proper mesh. A crank shaft 25, passes 65 through the receptacle 10, and carries the rear end of the riddle. The latter being secured thereto by clips 26 carrying perforations for a pin 27 that passes through the floor 23 of the riddle. By this means, when 70 the pins 27 are lifted from position, the riddle may be easily and quickly taken from the supporting shaft. The outside end of the shaft 25 passes downwardly, as at 29, to form a crank, with an outwardly extended 75 handle 30. The front walls 19 and 20 of the riddle are flexibly supported by chains 31 and 32, respectively. These chains are suitably fixed to the vertical walls of the receptacle 10, as at 33, the lower ends each 80 being provided with a ring 34 that passes into a perforation 35 in the respective side walls. When the main body part of the crank shaft 25 is down, as shown in Fig. 4, then the rear portion of the riddle is depressed, as shown in full lines in Fig. 2. In this position ashes may be placed on the riddle and the doors 15 and 16 closed. Then, by oscillating the shaft 29, the riddle will 85 serve the purpose of sifting the ashes. The finer portions will fall into the ash receiver 18 and the larger portions, that are of value, will remain upon the riddle. After the floating dust or ashes have been carried up through the pipe 11, and have become somewhat settled, then the door 15 may be 90 opened and the shaft 25 rotated one-half revolution. In this position the rear end of the riddle will be lifted to the position shown in dotted lines in Fig. 2, and the coal and coke remaining on the riddle will be dumped onto an inclined plate 36 into a suitable coal receiver that may be placed in the front of the plate, on the outside of the receptacle. Thus I provide a very simple 95 means for agitating the riddle to sift the ashes and also for elevating the rear end of the riddle, as a result of which the coal and coke remaining thereon, after the sifting process may be dumped therefrom.

The receptacle is provided with a damper 37 which may be closed so as to not inter-

fere with the draft in the smoke pipe 12, when the device is not in use. The projection 14 provides a means for catching the dust that may arise directly from the shovel, as the latter is placed on the front edge of the riddle in emptying the contents of the shovel into the riddle.

When the riddle is being used for sifting the ashes, a necessary movement may be given to it by oscillating the handle 30, and when it is lifted into the dotted line position, shown in Fig. 2 to discharge the contents thereof, the same oscillating operation should be effected so as to hasten the precipitation of the contents from the riddle. When the contents are being discharged from the riddle, in the manner described, it is not necessary to open the door 15, fully, and the door, in its partial open position, has a tendency to retain and direct the dust into the interior of the receptacle.

The receptacle 10 may be placed anywhere within the neighborhood of the smoke flue 12 and pipe may be led to it, instead of being directly connected, as shown, the object of the connection being to make the draft in the flue available for the purpose of carrying away the finer dust of the ashes.

When the ashes are being sifted, it is best to open the lower door 16 so that the draft through the casing 10 will be increased to actively carry the dust away.

While I have herein shown a single embodiment of my invention, for the purpose of clear disclosure, it will be manifest to persons skilled in the art, that changes may be made in the general arrangement and configuration of the parts within the scope of the appended claims.

Having described my invention, what I claim is:

1. A device of the character described having in combination a casing, or receptacle; a riddle therein having its front end flexibly

supported; a shaft having a crank upon which the rear end of said riddle directly rests whereby said rear end may be elevated to discharge its contents.

2. A device of the character described having in combination a casing, or receptacle; a riddle therein having its front end flexibly supported; a shaft having a crank upon which directly rests its rear end, whereby said rear end may be elevated to discharge its contents by rotating said shaft one half of one revolution; a door in the front end of the casing and a guide plate upon which to discharge the contents of the riddle.

3. A device of the character described having in combination a casing or receptacle connected to a smoke flue; a riddle therein; means to agitate the riddle from the outside of the receptacle and to subsequently elevate the rear end thereof and a door jamb projecting beyond the casing to direct the ash dust toward the flue.

4. A receptacle for ashes comprising a casing having its upper end connected to a smoke flue; a riddle having its front end suspended in the mid-portion of the casing; a crank upon which the rear end of the riddle directly rests and having a handle on the outside of the casing to agitate the riddle and to elevate one end thereof to discharge its contents and an ash receiver in the lower part of the casing below said riddle.

5. A receptacle for ashes comprising a casing connected at its upper end to a smoke flue; a jamb portion projecting laterally from the casing to provide a dust guide; a door near the bottom of the casing to accelerate the draft and a door in said jamb to close the casing.

In testimony whereof I hereunto subscribe my name.

ARTHUR W. BOCK.
